DISPLAY RACK

Charles A. Rolley, Millbrae, and Bruce D. Wallace, San Francisco, Calif., assignors to Rolley, Inc., South San Francisco, Calif., a corporation of California

Application February 18, 1957, Serial No. 44,886

Term of patent 7 years

(Cl. D80—10)

Fig. 1 is a front perspective view of a display rack showing our new design; and

Fig. 2 is a fragmentary rear elevational view on a reduced scale thereof.

We claim:

The ornamental design for a display rack, as shown.
